UNITED STATES PATENT OFFICE

LUCIAN E. PARKER, OF WADSWORTH, OHIO, ASSIGNOR TO THE OHIO MATCH COMPANY,
OF WADSWORTH, OHIO, A CORPORATION OF OHIO

TRANSFER MECHANISM FOR BOOK MATCH MACHINES

Application filed May 25, 1929. Serial No. 366,071.

This invention relates to a transfer mechanism for book match machines; that is to say, mechanism whereby the finished match books may be arranged in proper order for packing.

Machines for manufacturing book matches or, more particularly, machines for assembling the cards of matches and their covers to form match books, are generally so designed as to discharge the finished books in uniform order. This results in the necessity for providing some means whereby alternate books in a uniform series of same may be turned end for end so that, consequent to their characteristic wedge shape, they may stack evenly and thus be expeditiously handled and packed in customary predetermined multiples in the usual boxes provided for them and in which they are furnished to the trade.

The mechanism of the present invention is designed primarily to function in cooperation with a book match machine of a type in which the books are formed or assembled in multiples transversely of a carrying device which is so automatically operated as to advance the books with a step-by-step or intermittent motion. The pauses or dwells produced by such motion provide intervals in which the operations necessary to the assembling of the books may be performed, and these pauses or dwells are utilized also to permit functioning of the transfer mechanism of my invention.

The invention contemplates mechanism for engaging each individual match book, after its completion or assembly by the book match machine, and depositing it in predetermined end-for-end reversed relation to the book next subsequent to it in order of production or completion, and in means for automatically operating such mechanism in timed relation to the operation of the book match machine and its adjuncts, as I will proceed now to explain and finally claim.

In the accompanying drawings illustrating the invention, in the several figures of which like parts are similarly designated, Figure 1 is a plan view of the mechanism embodying my invention. Figs. 2, 3 and 4

are side elevations of same showing the parts in three distinct operative positions. Figs. 5 to 9, inclusive, are fragmentary perspective views of various details of the mechanism. Figs. 10, 11 and 12 are side views of three of the operating cams. Figs. 13 and 14 are side elevations of two of the operating links. Figs. 15 to 19, inclusive, illustrate the manner of handling the match books after their arrangement by the transfer mechanism.

In Fig. 2 I have indicated schematically, in broken lines, the carrier head A of a book match machine, and have shown two carrier members *a* and *a'* which form a part thereof and are provided with means (not shown, for holding the match books thereon. When the carrier members reach the positions shown at *a* and *a'*, each carries a finished match book, and they pause or dwell in this position while the machine is performing assembling operations upon other match books carried by the carrier head. This pause or dwell affords an interval, hereinbefore referred to, in which the mechanism is my invention may operate to transfer the finished match books from the carrier members to a conveyor belt or carrier *b* which conveys them to a position accessible to operatives by whom they are packed in the usual boxes.

According to the usual practice, the match books are made or assembled in aligned multiples of ten, transversely of the machine, and hence my mechanism is provided with ten simultaneously operated gripper members to transfer match books from carrier members in position *a*, and ten simultaneously operated gripper members to transfer match books from carrier members in position *a'*, as I will describe in detail later.

A shaft 1, Figs. 2, 3 and 4, preferably continuously driven by and in timed relation to the book match machine, carries a sprocket 2 operatively connected by a chain 3 with a sprocket 4 keyed to a back-shaft 5. The ratio of the speed of back-shaft 5 relatively to the shaft 1 is so determined by the ratio of sprocket 4 to sprocket 2 that

the various members forming my mechanism, all of which derive motion from back-shaft 5 will be properly timed to the operation of the carrier head A of the book match machine.

In parallelism with back-shaft 5 is a driven shaft 6 which derives its motion from and at the same speed as shaft 5 by means of complementary gears 7 and 8 keyed to the 10 shafts 5 and 6, respectively.

Journalled on shaft 6 and capable of oscillation relatively thereto is a pair of bracket members 9 rigidly connected transversely of the machine by a plate or bar 10 securely bolted to them as indicated at 11. The bracket members 9 are provided with lever extensions 12 to which are pivoted at 13 one of the ends of links 14 (Fig. 13) the other ends of which are forked, as shown 15 at 15, for sliding engagement with cross-heads 16 oscillably mounted on the back-shaft 5. The links 14 are provided with cam-follower rollers 17 which follow the 20 contour of the grooves 18 of similar cams 19 keyed to and rotatable with shaft 5. By 25 this arrangement it will be seen that, as the cams 19 rotate, the links 14 will be moved longitudinally of the machine and will impart an oscillatory movement to the bracket members 9.

The bracket members 9 (see Fig. 5) are provided with guideways 20 in which are mounted slides 21 rigidly connected transversely of the machine by rods 22. The 30 slides 21 carry cam-follower rollers 23 which follow the grooves 24 of similar cams 25, Fig. 10, keyed to and rotatable with shaft 6.

Carried by the rods 22 in spaced relation thereon is a plurality, preferably ten, of 40 gripper or transfer members. These gripper members comprise bearing blocks 26, Figs. 1 and 6, carrying heads 27 secured by means of cap screws 27' in adjusted position. Carried by the heads 27 are relatively 45 thin rigid upper jaws 28, and lower jaws 29 resiliently forced by springs 30 toward the jaws 28. Pivoted on the heads 27 relatively to the jaws 28 and 29 are stripper members 31 counterweighted as indicated at 32 to hold them normally clear of the jaws. The width of the jaws (transversely of the 50 machine) is less than the width of a match book, and hence when a match book is held between the jaws it will extend beyond the sides thereof and in the path of movement of the stripper members 31.

Pivoted in arms 33 journalled on the lower of the two rods 22 is a tripper bar 34 which 60 normally bears against the V-shaped backs 35 of the stripper members 31. This tripper bar 34 has laterally projecting ends 36 which may, under certain predetermined conditions be engaged by means hereinafter described to so operate the bar 34 as to trip 65 all of the stripper members 31 simultane-

ously to eject the match books from the jaws of their respective gripper members.

Obviously, as the cams 19 and 25 rotate, the bracket members 9 will be oscillated, as previously stated, and the slides carrying the gripper members will be reciprocated relatively to the bracket members.

The gripper members just described function to transfer match books from position *a* to the belt *b*.

The match books at position *a'* are transferred by the following mechanism:—On a shaft 37 carried by the frame of the machine are mounted arms 38 between which extend rods 39 similar to the rods 22. On the rods 39 is mounted a plurality (ten in the embodiment shown) of gripper or transfer members similar to the gripper or transfer members carried by the rods 22 but omitting the stripper members. These gripper or transfer members comprise the rigid, relatively thin upper jaws 40 and the spring-pressed lower jaws 41 (see Fig. 9).

The arms 38 are provided with lever extensions 42 to which are pivoted, as at 43, the free ends of links 44 (see Fig. 14) the opposite ends of which are forked as indicated at 45 for cooperation with cross-heads 46 carried by shaft 6. Cam follower rollers 47 carried by the links 44 engage the grooves 48 of cams 49 (see Fig. 11) keyed to and rotatable with shaft 6. By this arrangement it will be seen that, as the cams 49 rotate, the links 44 will be reciprocated and will impart oscillatory movement to the arms 38 and the gripper members carried thereby.

Mounted in suitable bearing members 50 is a rocking bar 51 (see Fig. 8) having trunnions 52 which enter the bearing members 50. This shaft is arranged between the two sets of gripper members and carries members which function in combination with both sets of gripper members in the operation of transferring the match books from the gripper members to the belt *b*.

The rocking bar 51 is provided with a lever extension 53 having a pin 54 which enters a slot 55 formed in one end of a rock lever 56 carrying at its opposite end a cam-follower roller 57 which engages a cam groove 58 formed in the face of the gear 8, Fig. 12. By this arrangement it will be seen that oscillatory movement is imparted to the rocking bar 51 and the members carried thereby.

The rocking bar 51 carries trip fingers 59 so laterally spaced as to cooperate at predetermined timed intervals with the lateral extensions 36 of the tripper bar 34 to cause the stripper members 31 to function. It also carries a plurality of blocks 60 so laterally spaced as to provide for depression between them of the gripper members 40—41 and provided with shoulders 61 so located as to

eject the match books from the jaws of these gripper members. Each of the blocks 60 carries a guide finger 62 to insure proper discharge of the match books upon the belt *b*.

As hereinbefore mentioned, the book match machine is so driven that its carrier head *A* has a step-by-step or intermittent motion, and the belt *b* is similarly driven by means of a pawl and ratchet mechanism 63, 64. By this arrangement the belt *b* will be stationary during the depositing thereon of the match books and will advance after they have been deposited, as will hereinafter be more clearly pointed out.

The operation of the apparatus, and the handling of the match books for packing are substantially as follows:—

Assuming that the book match machine is in operation and that power is transmitted therefrom to the shaft 1 and ratchet mechanism 63—64, the carrier head *A* will have imparted to it a step-by-step movement and will intermittently present in positions *a* and *a'* finished match books. Also the shaft 1 will, through its chain and sprocket gearing 2, 3, 4 impart continuous rotation to shaft 5 which, through gears 7 and 8, will drive all of the members forming the mechanism of my invention. Furthermore, the belt *b* will be advanced intermittently, toward the right, in timed relation to the operation of transfer mechanism.

The carrier head *A* having paused, the jaws 28—29 and 40—41 of each of the gripper members will engage a match book at positions *a* and *a'*, respectively, as shown in Fig. 2. Now, as the shafts 5 and 6 and their cams rotate, the bracket members will be so oscillated by cams 19 through links 14 and the plurality of gripper members carried thereby so radially retracted by means of the cams 25 through rollers 23 and slides 21 that the whole assembly of these gripper members will assume substantially the position shown in Fig. 3. However, it is to be understood that at this time the high point *c* of cam groove 58 has not yet reached roller 57 of rock lever 56. With the bracket members 9 and grippers held substantially in this depressed position, the high point *c* of cam groove 58 operates on roller 57 to impart a quick oscillation to the rocking bar 51. This results in a quick depression of the trip fingers 59 into engagement with the lateral extensions 36 of tripper bar 34 and causes the tripper bar to simultaneously operate all of the stripper members 31 to eject the match books held between the jaws 28—29 and cause them to fall in substantially uniform alignment transversely of belt *b* which at this time is stationary. The match books thus deposited take the position as to end-wise arrangement indicated at *d*, Fig. 16. Meantime, the arms 38 and the grippers carried by them have been moved to the

position shown in Fig. 4 by the operation of cams 49 upon links 44.

As gear 8 continues its rotation, its cam groove 58 will cause the rocking bar 51 with its trip fingers 59 and guide fingers 62 to again assume substantially the position shown in Figs. 2 and 4, and also the continued rotation of cams 19 will cause the gripper assembly carried by the bracket members 9 to be returned to the position shown in Figs. 2 and 4.

As the gripper assembly carried by the members 9 is elevated out of the way, the grippers carried by the arms 38 will be moved into the position shown in Fig. 4, and the final portion of the downward movement of the gripper members will cause the portions of the lower edges of the match books which extend laterally beyond the sides of the jaws 40—41 to strike against the shoulders 61 of the blocks 60 and said books will be ejected from the jaws so as to fall upon the belt *b* and upon the match books previously deposited upon the belt by the gripper members 28—29 with their ends reversed relatively to such latter match books, as shown at *e*, Fig. 16.

Both sets of gripper members having deposited the match books carried by them upon the belt, the pawl and ratchet mechanism 63—64 will be automatically operated to advance the belt to the right the predetermined required distance to receive the next match books to be deposited in proper relation to those already upon the belt.

The operations described are continued during the period of operation of the book match machine, the finished match books being thus successively deposited in relative recumbent arrangement upon the belt in uniform series with alternate books reversed end-for-end longitudinally of the belt, as shown in Figs. 15 and 16.

Book matches are ordinarily furnished to the trade in boxes containing fifty match books arranged in two rows, edge up, and it will thus be seen that, with ten rows longitudinally of the belt, if an operative counts off twenty-five books in longitudinal order, there will be two hundred and fifty books in the area transversely of the belt determined by such count of twenty-five books, or enough to fill five boxes.

I have found that the operatives employed in packing book matches in the usual boxes of fifty books become very expert in counting off a longitudinal series of twenty-five books. In fact they become so proficient in this respect as almost to sense the multiple of twenty-five books. With the books in end-for-end uniform order, this proficiency is enhanced and the packing operation greatly facilitated and expedited. In Figs. 15 to 19, inclusive, I have illustrated one manner in which the match books may be arranged

in multiples of two hundred and fifty books (ten series of twenty-five books each) two of such series only being shown as adequate to a clear understanding of the various operations employed.

As the belt *b* progresses, carrying the properly arranged match books, clear of the right hand side of the machine, an operative will place a block *f* (Figs. 15 and 16) 10 in position against the first transverse row of match books in the longitudinal series, and then counting or sighting off twenty-five books, longitudinally, will insert a scoop member *g* and, while holding the scoop member *g*, will move the block *f* to the left, thus moving up the match books from recumbent into intimate stacked arrangement as shown in Fig. 17. Then a block *f'* will be 15 positioned back of the scoop member *g* and the scoop member withdrawn, the match books being held in stacked relation between the blocks *f* and *f'*, as shown in Fig. 18. In this manner, it will be seen that the match books are arranged in proper multiples of 20 twenty-five books in close stacked relation between the blocks *f* and *f'* and are in suitable arrangement for transfer to the customary boxes. As will be apparent from 25 an inspection of Fig. 16, the blocks *f* and *f'* are of such cross sectional dimensions that when the match books are arranged as shown in Figs. 17, 18 and 19, the upper ends of the books will project above the top surfaces of the blocks sufficiently to permit an operative to grasp them as indicated in Fig. 19 and transfer bodily a series of twenty-five stacked books from the belt *b* to the box.

It will be understood that, ordinarily, 30 there will be two operatives assigned to each machine at the packing station. One of these operatives will count off the match books in multiples of twenty-five and arrange them between blocks *f* and *f'* upon the belt, a sufficient supply of such blocks being kept at hand for the purpose. The books thus arranged will be fed along with the belt to the other operative who will 35 merely pick them up in the manner indicated in Fig. 19 and deposit them in the boxes.

It will thus be seen that I provide a 40 relatively simple and very efficient mechanism for arranging match books in proper alternate end-for-end stacked relation, and thus enable operatives to readily handle the 45 match books in a very expeditious and efficient manner for packing.

Although I have indicated in Fig. 2 a portion of a particular type of book match machine, it is to be understood that the 50 mechanism of my invention is not limited to its combination with such a machine, but may be used with any type of book match machine to which the operations producing its various functions may apply.

Various changes are contemplated as

within the spirit of the invention and the scope of the following claims.

What I claim is:—

1. In a transfer mechanism for book match machines, means for engaging each match book after its completion by said machine and transferring it to a carrier, the operation of said means being such that successive match books are deposited upon said carrier in end-for-end reversed partially overlapping relation whereby they will stack evenly, and means for operating said transfer mechanism in timed relation to the operation of the book match machine. 70

2. In a transfer mechanism for book match machines, means for grasping each match book after its completion by said machine and transferring it to a horizontally disposed carrier, the operation of said means being such that successive match books are deposited by gravity upon said carrier in recumbent position and in end-for-end reversed partially overlapping relation whereby they will stack evenly, and means for operating said transfer mechanism in timed relation to the operation of the book match machine. 80

3. In a transfer mechanism for book match machines, a carrier, a pair of transfer members, each of said transfer members adapted to receive a match book and deposit it by gravity upon said carrier, and means for operating said transfer members in timed relation to the operation of said book match machine and to each other, one of said transfer members functioning to deposit match books in a predetermined end-wise position recumbent relatively to said carrier and the other transfer member functioning to deposit match books in reversed endwise position relatively to the carrier and in partially overlapping recumbent relation to the match books previously deposited. 90

4. In a transfer mechanism for book match machines, two transfer members adapted to simultaneously receive match books from said machine and to successively deposit same, said members functioning to deposit the books in end-for-end partially overlapping arrangement, and means for operating said members in timed relation to each other. 100

5. In a transfer mechanism for book match machines, two transfer members adapted to simultaneously receive match books from said machine and to successively deposit same, said members functioning to deposit the books in partially overlapping relation upon each other in end-for-end successive arrangement, and means for operating said members in timed relation to each other. 110

6. In a transfer mechanism for book match machines, the combination with a book match machine adapted to present fin- 120

ished match books at two separate positions, of two transfer members one of which will receive match books from one of such positions and the other from the other position, and means for operating said transfer members in timed relation to said machine and to each other whereby they may deposit the match books, the two transfer members adapted to deposit the books received by them in alternate end-for-end arrangement.

7. In a transfer mechanism for book match machines, the combination with a book match machine adapted to present finished match books at two separate positions, of two transfer members one of which will receive match books from one of such positions and the other from the other position, and means for operating said transfer members in timed relation to said machine and to each other whereby they may deposit the match books, one of said transfer members operating to deposit all books received by it in predetermined endwise arrangement, and the other transfer member operating to deposit all books received by it in reverse endwise arrangement relatively to the former.

8. In a transfer mechanism for book match machines, the combination with a book match machine adapted to present finished match books at two separate positions, of two transfer members one of which will receive match books from one of such positions and the other from the other position, and means for operating said transfer members in timed relation to said machine and to each other whereby they may deposit the match books, one of said transfer members operating to deposit all books received by it in predetermined endwise arrangement, and the other transfer member operating to deposit all books received by it in reverse endwise arrangement relatively to the former, each book overlapping the one next previously deposited.

9. In a transfer mechanism for book match machines, the combination with a book match machine and a horizontally travelling carrier, of two sets of transfer members arranged to receive match books from said machine, and means for operating said sets of members in timed relation to said machine and to each other, whereby they will deposit the match books by gravity upon said carrier in overlapping recumbent longitudinal series.

10. In a transfer mechanism for book match machines, the combination with a book match machine and a carrier, of two sets of transfer members arranged to simultaneously receive match books from said machine, and means for operating said sets of members in timed relation to said machine and to each other, whereby they will

successively deposit the match books upon said carrier in overlapping recumbent longitudinal series, the transfer members of one set operating to deposit the match books in end-for-end reversed arrangement relatively to the books deposited by the members of the other set.

11. In a transfer mechanism for book match machines, the combination with a book match machine having an intermittently movable carrier head and an intermittently horizontally travelling carrier member operating in relatively timed intervals, of a plurality of transfer members adapted to receive match books from said carrier head and to deposit them by gravity in predetermined relation on said carrier member, and means including constantly driven cam mechanism for intermittently operating said transfer members in timed relation to the operation of said carrier head and carrier member.

12. In a transfer mechanism for book match machines, the combination with a book match machine having an intermittently movable carrier head and an intermittently horizontally travelling carrier member operating in relatively timed intervals, of two sets of transfer members adapted to receive match books from said carrier head and to deposit them by gravity in predetermined overlapping end-for-end relation on said carrier member, and means including constantly driven cam mechanism for intermittently operating said sets of transfer members in timed relation to each other and to the operation of said carrier head and carrier member.

In testimony whereof I have hereunto set my hand this 23d day of May, A. D. 1929.

LUCIAN E. PARKER.
